STOCKING STRETCHER

Russell J. Wolfe, Buffalo, N. Y.

Application May 6, 1947, Serial No. 138,857

Term of patent 14 years

(Cl. D49—1)

To all whom it may concern:

Be it known that I, Russell J. Wolfe, a citizen of the United States, residing at Buffalo, in the county of Erie and State of New York, have invented a new, original, and ornamental Design for a Stocking Stretcher, of which the following is a specification, reference being had to the accompanying drawing, forming a part thereof.

Fig. 1 is a front view of a stocking stretcher showing my new design;

Fig. 2 is a side elevational view;

Fig. 3 is a sectional view taken on line III—III of Fig. 2; and

Fig. 4 is a sectional view taken on line IV—IV of Fig. 2.

I claim:

The ornamental design for a stocking stretcher, as shown.

RUSSELL J. WOLFE.
